UNITED STATES PATENT OFFICE.

ELI CATLIN, OF POST OAK, TEXAS.

WELL-DRILLING APPARATUS.

SPECIFICATION forming part of Letters Patent No. 288,975, dated November 27, 1882.

Application filed July 18, 1883. (No model.)

To all whom it may concern:

Be it known that I, ELI CATLIN, a citizen of the United States, residing at Post Oak, in the county of Jack and State of Texas, have 5 invented a new and useful Well-Drilling Apparatus, of which the following is a specification, reference being had to the accompanying drawings.

This invention relates to machines for drilling wells and the like; and its object is to provide a machine possessing superior advantages in point of simplicity, convenience, ease of operation, inexpensiveness, and general efficiency.

15 In the drawings, Figure 1 is a perspective view of my improved well-drilling machine in position for operation. Fig. 2 is a top view of the same. Fig. 3 is a front end view. Fig. 4 is a vertical transverse sectional view taken 20 through the operating-shaft. Fig. 5 is a detail sectional view of the ratchet mechanism by which the drill-shaft is operated. Fig. 6 is a detail perspective view of the direct mechanism for throwing the rear drum out of gear. Figs. 7, 8, and 9 are details.

25 Referring to the drawings, A designates the main supporting frame or truck, which comprises the front axle, B, having wheels C C, the rear axle, D, having wheels E E, and the 30 connecting-reach F. The drilling mechanism is secured on this frame, and is therefore adapted to be conveniently transported from place to place.

G G are the longitudinal side pieces of the 35 drill-frame, these being connected at their front ends by a bolster, H, that is united to the front axle by the king-bolt I, and from which project uprights J J at the sides of the machine.

40 K is a standard about centrally arranged on the reach F; and L is the main operating-shaft of the machine, which has its bearings M M in the said standard and on one of the side beams, G G, and carries a main gear-wheel, N. At the inner end of the shaft L is 45 fixed a ratchet wheel or disk, O, that is enclosed within a plate or arm, P, that is arranged loosely on the same end of the shaft, and carries a pawl, Q, that is forced into engagement with the ratchet-disk by means of a spring, R, as shown. In the projecting arm 50 of the plate P are formed a series of perfora-

tions, S, in any one of which the end T of a rod, U, is adapted to be inserted. This rod is connected by a rope, V, with the drill-rope 55 W, which passes over a pulley, X, at the top of the derrick-frame Y, that comprises two convergent uprights, Z Z, hinged at their lower ends to the uprights J J, as shown at A² A², so that they can be folded down rearwardly 60 when the machine is not in use, and rested on a bolster, B², arranged at the rear end of the machine. This derrick-frame is supported, when in upright position, by inclined braces C² C², that are removably connected to the uprights Z Z, and are likewise secured at their rear lower ends, D² D², to horizontal beams E² E², which are elevated above the beams G G by uprights F² F², and carry the bolster B². When the derrick-frame is lowered, the braces 70 C² C² are disconnected and laid on top the machine.

In operation, when the shaft L is turned toward the front of the machine, the disk O engages the pawl Q on the arm P, and carries the latter around, as shown by the arrow, Fig. 5 of the drawings, to the point designated by G². During this movement of arm P it of course carries the rod U, which draws on the drill-rope and lifts the drill. As soon as the arm P reaches the point G², the pawl becomes disengaged, and will pass over the teeth of the ratchet O as the arm P flies around and the drill suddenly drops. The pawl Q will now be again in engagement with the teeth of the 85 disk, and the operation will be repeated with each revolution of the shaft L. When the shaft L is turned in the opposite direction—i. e., toward the rear end of the machine—(which movement is necessary to wind the 90 drums, as hereinafter specified,) the arm P will retain its position, and the pawl Q will slip over the teeth of the ratchet O as the latter revolves with the shaft.

The revolution of the shaft L can be effected 95 by any suitable power, but is preferably operated by the horse-power herein shown and specified. This horse-power—a horizontally-anchored inverted crown-wheel, H², that is journaled on an axle, I²—carries the sweep J², 100 and meshes with a pinion, K², on a shaft, L², having bearings M² M² in ground-blocks, N². A tumbling-rod, O², transmits the motion of this shaft L² to the shaft L. Wheels P² P² are

- adapted to be secured on the axle I^2 , so that the horse-power can be readily transported by attaching it at the rear end of the drill when the latter is moved from place to place.
- 5 Q^2 is a transverse shaft arranged to slide in bearings $R^2 R^3$ on the beams $E^2 E^3$, and carrying a heavy fly-wheel, S^2 , at one end and a pinion, T^2 , near its other end, which pinion meshes with the gear-wheel N . At the end of shaft Q^2 is arranged a circumferentially-grooved disk, U^2 , that is engaged by a semi-circular rod, V^2 , carried in the bifurcated end W^2 of a shifting-lever, X^2 , that is fulcrumed on a standard, Y^2 , projecting from one of the beams G . By operating this lever the pinion T^2 may be thrown into and out of engagement with the gear-wheel N . It is designed to be out of engagement when the drill is out of operation and the drums are being wound, but should always be in operation with the drill. This fly-wheel will secure an even and steady motion to the drill mechanism, and will prevent the horse from pitching forward when the drill drops. Its more important function is to prevent the drill from sticking after it has dropped, as the inertia of the wheel will lift the drill the instant it reaches its downward limit.
- 20 Z^2 is the drum on which the drill-rope W is wound. This drum has bearings A^2 at one end on one of the beams G , and has its bearings at its other end in a box, B^2 , arranged on the other beam G , to bring a gear-wheel, D^2 , on the drum into engagement with the gear-wheel N when it is desired to wind the rope W on the drum. The sliding box B^2 is operated by a lever, E^2 , connected to the said box by a pivoted rod, F^2 . The end of the drum-shaft is provided with a friction wheel or disk, G^2 , around which is arranged a flat brake-spring, H^2 , secured at one end, I^2 , to the beam G , and having its other end pivotally connected, as shown at J^2 , to an angular lever, K^2 , that is connected by means of a pivoted rod, L^2 , with a lever, M^2 , by which the spring-brake can be operated as desired. Normally the disk G^2 will be back against the spring H^2 , to brake the drum as the drill-rope unwinds.
- 25 At the rear end of the machine is arranged another drum, N^2 , having one end bearing, as at O^2 , on the beam G , while its other end, P^2 , bears in the top of a lever, R^2 , that is fulcrumed in a slot, Q^2 , in the other beam G . The lever R^2 is operated by means of a lever, S^2 , and a connecting-rod, T^2 , to shift the gear-wheel U^2 into engagement with the wheel N when it is desired to wind up the drum. The rope V^2 , that carries the bucket for drawing water, is adapted to wind on this drum, from which it passes over a pulley, W^2 , in the derrick-frame. When it is desired to wind the rope V^2 upon the drum, the latter is thrown into engagement with the gear-wheel N , and when released from this engagement a friction wheel or disk, X^2 , on the shaft of the drum will come against a brake-block, Y^2 , on

the beam G and hold the drum so that the descent of the bucket will not be too rapid.

At the rear end of the machine is arranged a transverse brake-bar, Z^2 , carrying shoes $A^4 A^4$, that engage the rear wheels, $E^4 E^4$, and provided with an arm, B^4 , by which the brake can be operated. This operating-rod can be connected by a removable rod, C^4 , with the lever that operates the front drill-drum, so that the machine will be braked in position during operating by reason of the position of this lever.

The operation and advantages of my invention will be readily understood and appreciated. It is very simple and inexpensive in construction, and can be easily and conveniently operated.

I am aware that the fixed ratchet and loose arm carrying the pawl for operating the drill are old, and I therefore do not broadly claim this as of my invention.

I claim as my invention—

1. The combination of the rotary main shaft, the drill-rope, mechanism on the shaft connecting with the drill-rope to raise the drill, a gear-wheel on the shaft, a shaft having a pinion engaging this gear-wheel, and a fly-wheel fixed on this latter shaft, whereby sticking of the drill is obviated, substantially as set forth.

2. The combination of the frame of the machine, comprising in its construction a derrick-frame at its front end, having suitably-arranged pulleys, a centrally-arranged main rotary operating-shaft, a gear-wheel fixed on the said shaft, a winding-drum arranged in shifting bearings at each side of the main shaft, gear-wheels fixed on the drums and arranged to mesh with the gear-wheel on the main shaft, mechanism for shifting the drums, the drill-rope arranged on the front drum, mechanism on the main shaft connecting with the drill-rope and adapted to operate the same, and the bucket-rope arranged on the rear drum, substantially as and for the purpose set forth.

3. The combination, with the drill-rope drum arranged in the shifting bearings and provided with the friction-disk, of the spring-brake extending around the said disk and connected at its free end with lever-operating mechanism, substantially as and for the purpose set forth.

4. The combination of the rotary main shaft fixed in its bearings, and carrying mechanism adapted to operate the drill-rope, a gear-wheel arranged on the said shaft, the drum having its bearing in a sliding box, mechanism for operating the sliding box, the drill-rope wound on the said drum, a gear-wheel fixed on the drum and adapted to be thrown into engagement with the gear-wheel on the main shaft, a friction-disk arranged on the shaft of the drum, and a spring-brake engaging the said friction-disk, substantially as and for the purpose set forth.

5. The combination of the main rotary shaft having fixed bearings, a gear-wheel arranged on the said shaft, a rotary drum having its

bearing in the top of a lever, a gear-wheel arranged on the said shaft and adapted to be thrown into engagement with the gear-wheel on the main shaft, means for operating the lever that forms one of the end bearings of the drum, a friction-disk arranged on the shaft of the drum, and a friction-block arranged to engage the said disk, substantially as and for the purpose set forth.

In testimony that I claim the foregoing as to my own I have hereto affixed my signature in presence of two witnesses.

ELI CATLIN.
